UNITED STATES PATENT OFFICE.

THOMAS R. WEYANT, OF NEW YORK, N. Y.

PILLOW-SHAM HOLDER.

SPECIFICATION forming part of Letters Patent No. 413,119, dated October 15, 1889.

Application filed June 5, 1889. Serial No. 313,191. (No model.)

To all whom it may concern:

Be it known that I, THOMAS R. WEYANT, of the city, county, and State of New York, a citizen of the United States, have invented 5 certain new and useful Improvements in Combined Pillow-Sham Holder and Mosquito-Frame Support, of which the following is a specification.

This invention relates to a combined pillow-sham holder and mosquito-frame support which can be applied with great facility to the bed-posts of any bedstead, and which forms not alone a simple and conveniently-operated holder for the pillow-sham, but also 15 a supporting device for an arm by which the mosquito-frame is supported.

The invention consists of the combination, with a pillow-sham holder, of brackets for supporting the same, said brackets being 20 made integral with a rectangular clamping-piece which is applied to the bed-post and supported thereon by a second angular clamping-piece and a fastening-screw that connects said clamping-pieces. One clamping-piece is 25 provided with a beveled face and the other with a beveled flange which overlaps the beveled face and permits thereby the adjustment to different sizes of posts. The bracket clamp-piece is provided with a socket-hole for 30 supporting the arm of the mosquito-frame. It is also provided with a lug that meshes with the teeth of a pinion on the pivot-shaft of the pillow-sham holder, so as to lock the same in proper position.

35 In the accompanying drawings, Figure 1 represents a perspective view of a bedstead with my improved combined pillow-sham holder and mosquito-frame support attached to the posts of a bedstead. Fig. 2 is a horizontal section drawn on a larger scale through the head-piece and posts of the bedstead, showing the pillow-sham holder and its supporting-bracket clamps in top view and partly in horizontal section. Figs. 3 and 4 are a 40 side elevation and horizontal section of the supporting-clamp, drawn on a still larger scale.

Similar letters of reference indicate corresponding parts.

45 Referring to the drawings, A represents the head-piece of a bedstead, and B B the posts

of the same. C is the pillow-sham holder, which is made of the usual construction, and provided at both ends with pivots d d, that are supported in brackets d' of the clamps D D, 55 which are applied to the bed-posts B B. One of the brackets d' of one of the clamps D is provided with a fixed lug or pin e, that is made integral with said bracket, and which engages a pinion e' on one end pivot of the pillow-sham holder C. The pivot at the other end of the pillow-sham holder is made of sufficient length to permit the lateral shifting of the pillow-sham holder and its pivots in the supporting-brackets, so as to permit of the 60 pin e clearing the teeth of the pinion e', so that the pillow-sham holder can be raised or lowered, as required. When the pillow-sham holder has been properly adjusted, it is shifted back into its normal position, so that the lug 70 or pin e can re-engage the pinion e' and lock the holder thereby rigidly in position, as shown in Figs. 2 and 4. The bracket-clamps which support the pillow-sham holder are each composed of two rectangular sections b 75 b', the sections b b being each made integral with the supporting-brackets of the pillow-sham holder, and provided with an opening f, which forms a socket for a bent arm F, that can be inserted into said socket-hole, and is 80 provided with a shoulder, so as to rest on the section b. The upper end of the supporting-arm F is provided with a hook-shaped end for receiving the eye of the mosquito-frame, which is suspended therefrom. When the mosquito-frame is not required, the arm F is removed, the clamp-piece being then used as a pillow-sham supporter in the usual manner. 85

The rear sections b' of the clamps B are 90 screwed to the rear part of the bed-post B and each connected by a screw-bolt M, passing through the same, with the section b, which has a threaded socket for said bolt, as shown clearly in Fig. 4. Each rear section b' is provided with a beveled forwardly-extending 95 flange b², which fits on the beveled face of the front clamp b, and permits thereby the adjustment of the clamp to any size of bed-post. By applying the screw-bolt the two clamp-sections are firmly clamped to the bed-post, a layer N of felt or other suitable cushioning material being interposed between the 100

sides of the bed-post and the inner surface of the clamp-sections, so as to prevent the chafing and scratching of the bed-post. By loosening the screw-bolts M the pillow-sham holder and its supporting-brackets may be readily removed.

5 The parts can be readily applied and form a strong and reliable support for the pillow-sham holder, as well as for the mosquito-frame 10 when the same is desired to be used.

Having thus described my invention, I claim as new and desire to secure by Letters Patent—

15 1. A clamp for pillow-sham holders, composed of a front section provided with a bracket for supporting a pillow-sham holder, a rear section adapted to be secured to a bed-post, and a connecting screw-bolt engaging a threaded socket of the front section, substantially as set forth.

20 2. A clamp for pillow-sham holders, composed of a front section provided with a

bracket for a pillow-sham holder, a rear clamp adapted to be attached to a bed-post and provided with a beveled flange sliding on a beveled face of the front section, and a connecting screw-bolt engaging an interiorly-threaded socket of the front section, substantially as set forth. 25

3. A supporting-clamp adapted to be attached to a bed-post and composed of a front section, a rear section, a connecting screw-bolt engaging a threaded socket of the front section, said front section being provided with a socket-hole, and a bent arm fitting 30 therein and adapted to support a mosquito-frame, substantially as set forth. 35

In testimony that I claim the foregoing as my invention I have signed my name in presence of two subscribing witnesses.

THOMAS R. WEYANT.
